AUTO WINDOW GARNISH MOLD COVER

Hector F. Strickland, Macon, Ga.

Application March 17, 1948, Serial No. 15,393

4 Claims. (CL. 296—44)

1

The present invention relates to improvements in auto window garnish mold covers and is a continuation-in-part of my similarly entitled application filed February 19, 1947, Serial No. 729,430.

In common with the objects of my prior application aforesaid, it is the purpose of the present invention to provide a garnish mold cover adapted to be placed over the factory made conventional window garnish mold which extends along the lower window sill edge of automobile window frames with the object of providing a readily interchangeable mold cover for being snapped over the conventional garnish mold when the same has become worn, discolored or suffered loss of its paint or other finish, and whereby also the mold cover may be fitted over the conventional garnish mold when new in order to protect the same from the rays of the sun which are apt to crack and peel the paint or finish and thus expose the underlying metal to the corrosive action of the oxygen of the atmosphere.

Another object of the invention is to provide an improved auto window garnish mold cover in which such cover will obscure unsightly rust, protect occupants' sleeves when resting on door window sills, and lend added attraction and decorative door and window trim.

A further object of the invention resides in providing an interchangeable garnish mold cover so constructed that it may be applied to the windows on either side of the vehicle and so constructed and arranged that the same will snap on substantially instantaneously over the customary manufactured garnish mold.

A still further object of the invention is to provide an improved interchangeable auto window garnish mold cover which may be made from standard gage spring brass rolled in a tube-like form, chromium plated, and given an initial set or form whereby the same may be quickly applied with a spring snap upon the regular manufactured garnish mold.

With the foregoing and other objects in view, the invention will be more fully described hereinafter and more particularly pointed out in the appended claims.

In the drawings, in which like parts are denoted by the same reference characters throughout the several views,

Figure 1 is a fragmentary perspective view showing a vehicle equipped with an improved auto window garnish mold cover constructed in accordance with the present invention;

2

Figure 2 is a fragmentary perspective view taken on an enlarged scale along the line 2—2 in Figure 1; and

Figure 3 is a perspective view of the improved garnish mold cover apart from the vehicle.

Figure 4 is a transverse vertical sectional view of the garnish mold cover on an enlarged scale.

Referring more particularly to the drawings, 10 designates generally an automobile having a window 11 with a vertically movable glass 12 operating in the usual slot made between the outside body member 13 and the internal door panel 14 which is covered with upholstery 15 as indicated particularly in Figure 2.

15 The conventional or regular garnish mold is indicated at 16. It is unnecessary to make any modification in this factory made garnish mold 16. This garnish mold 16 is, for convenience of illustration, shown to be of a form currently included in Ford automobiles, and it is transversely curved so as to fit over the inner upper corner portion of the door panel 14 and has an upper portion extending substantially all the way across the upper transverse edge of the door panel 14 and also has an extended portion lying downwardly a substantial distance from the upper inner edge of the door panel down along the interior face thereof.

This factory made garnish mold 16 has a substantially vertical flange 17 turned inwardly with respect to the concave side of the mold 16 and extending down to the upholstery on the outer upper edge of the door panel 14. An inwardly turned and curled flange 18 is made along the inner lower longitudinal edge of the factory made mold 16 in order to lie close against the upholstery 15 while preventing no sharp edges through or to the interior surface of the mold.

20 A V-shaped inwardly crimped portion 19 is made in the mold 16 between its intermediate part and the lower inner flange 18. This crimp is substantially V-shaped in cross section with the inner portion thereof extending close to the upholstery 15.

25 In accordance with the present invention, a mold cover is provided consisting of a resilient strip 20, curved transversely to conform generally to the curvature of the standard garnish mold 16.

The cover strip 20 spans substantially the entire width of the upper edge of the door panel 14 and also extends down a substantial distance over the inside face of such door panel, being made in a convex curve about the inner upper corner of the door panel 14. The external upper edge of the cover strip 20 is turned down from

the curved body 16 to constitute an upper longitudinal edge flange 21 which is substantially upright but may be at a substantially right angle. From an inspection of Figure 3 it will be clear that the upper flange 21 occupies only the intermediate portion of the strip 20 and the upper edge of the strip 20 for a distance inwardly of the ends thereof is flangeless. In other words, the end portions of the upper edge are both devoid of any flange and the flange 21 only extends over the intermediate portion of the length of the strip 20. At the flangeless end portions of the upper edge the strip is bent angularly inward with reference to the concave side of the laterally rounded strip 20 and flattened as indicated at 22 and 23. The mold cover strip 20 is generally rounded from upper end 21, 22 and 23 and is made of a size to encompass the standard mold 16 as indicated in Figure 2. This mold cover strip 20 is preferably made of metal or some other material possessing inherent elasticity.

The cover strip 20 is longitudinally crimped as indicated at 24 in alignment with the V-shaped inwardly crimped portion of the standard mold 16 whereby to lie in contact therewith. Extending off this crimped section 24 at the lower edge of the strip 20 is a channel flange formed by the substantially parallel walls 25 and 26 and the bottom wall 27; these walls adapted to conform rather closely to the beaded lower edge 18 of the standard mold 16. In fact the wall 26 might be bent slightly inward toward the wall 25 to form an interlocking fit with the inner flange 18 of the standard mold 16 as shown in Figure 2.

The mold strip 20 is given an initial bend whereby the flanges 25, 26 and 27 are separated by a somewhat shorter distance than the flanges 17 and 18 of the standard mold 16. In this way the outer flange 21 will snap over the included flange 17 and the flange wall 26 will snap over the included flange 18 when pressure is put upon the intermediate bowed portion of the outer mold cover strip 20. The relative mutual formation of the flanges 17, 21 and 18, 26 is such as to cause these flanges to interlockingly engage when snapped in place, the engagement being retained by the stress inherent in the material of the cover strip 20 tending to regain its shape after being put under the strain of snapping into place. The mold cover strip 20 will be slightly spread and held in the slightly spread condition when in place as shown in Figure 2. Its tendency to elastically contract will cause its flanges 21, 26 to hug the outer faces of the complementary flanges 17, 18 of the standard mold 16. As a matter of fact, the flange wall 26 at the inner lower end of the cover strip 20 will extend upwardly toward the flange 21 at approximately a 45° angle to the vertical.

The standard mold 16 becomes an anchorage to which to apply the improved mold cover 20.

It will be noted that there is no squeaking noise possible incident to vibration in the mold cover.

The improved mold cover 20 is made interchangeable by the flangeless upper edge portions 22 and 23. These edges are straight and are preferably polished. The flangeless end portions 22 and 23 are for the purpose of fitting under the rubber weatherstrip below the vent glass 29. A pivot 30 for the vent glass is carried on the outer edge of the door panel 14 and extends up in slightly spaced relation from the standard mold 16 so that sufficient space therebeneath is permitted to allow the cover strip 20 to be inserted therebeneath. The straight edges 22 and 23

make it possible to reverse the strip 20 end for end and therefore the strip may be placed on the windows on either side of the car. This enables a single form of strip to be made which is applicable to all window sills of the car. This also enables one set of dies to be made for the manufacture of the device. In other words this interchangeability reduces cost of dies and cost of the metal and facilitates the installation.

The mold cover strip 20 extends longitudinally in a straight line and is of a length to encompass the horizontal straight line portion of the lower sill of the window frame. In other words this cover strip 20 does not extend to the curved portions of the window frame at the ends of the sill.

The ends of the strip are curved as indicated at 31 to enable the inner lower edge of the strip 20 to be longer than the upper outer edge thereof. This enables me to take advantage of the greater length of the straight line portions of the standard mold at the inner edge thereof.

It will be appreciated that the improved device is interchangeable from one model to another and from one make automobile to another without involving any basic change in construction except in essential and non-essential lengths and widths. The convex side of the cover strip 20 represents the finished side of the mold. This may be chromium finished brass or it may be of stainless steel or other desired material. Once the finish has been produced in a polished effect the same will never require refinishing in a lifetime. The materials used heretofore in the art have required repainting, rebuffing and polishing as the surface wears off, cracks or rusts.

It will be understood that the flange 26 hooks upwardly beneath the edges 18 extending along a line forming approximately a 45° angle with the vertical plane defined by the wall of the flange 21, thereby causing no pressure against quarter panel cover 15. If such pressure existed at the point 26, it would be damaging to the fabric 15.

The V-crimp 19 has been added horizontally along the lower edge for the purpose of strengthening and retaining resiliency in the embodiment of the mold cover.

While I have disclosed herein the best form of the invention known to me at the present time, I desire it to be understood that I reserve the right to make changes and modifications in the herein described embodiment of the invention provided such changes fall within the scope of the following claims.

What I claim is:

1. For use with the conventional auto window garnish mold extending along the lower window sill of a vehicle window frame, a garnish mold cover comprising a transversely bowed resilient strip having an inner lower edge and an upper outer edge, said strip having a flange along its inner lower edge and a flange along its upper outer edge extending only along the intermediate portion of the cover with the end portions of the cover devoid of flanges at both ends to enable the mold cover to be reversed end for end for interchangeability for fitting the right and left windows of the vehicle, said upper outer edge flange adapted to clip over the top edge of said garnish mold and said inner lower flange adapted to clip over the bottom of said garnish mold, said flanges being spaced apart in unsprung condition a shorter distance than the distance between the top and bottom of the garnish mold to enable the cover to be sprung over the garnish mold with the

opposed flanges interlocking with the longitudinal edge portions of the garnish mold.

2. For use with the conventional auto window garnish mold extending along the lower window sill of a vehicle window frame, a garnish mold cover comprising a transversely bowed resilient strip having an inner lower edge and an upper outer edge, said strip having a flange along its inner lower edge and a flange along its upper outer edge extending only along the intermediate portion of the cover with the upper end portions of the cover devoid of flanges at both ends to enable the mold cover to be reversed end for end for interchangeability for fitting the right and left windows of the vehicle, said upper outer edge flange adapted to clip over the top edge of said garnish mold and said inner lower flange adapted to clip over the bottom of said garnish mold to enable the cover to be sprung over the ordinary garnish mold with the opposed flanges interlocking with the longitudinal edge portions of the conventional garnish mold, the length of said cover being approximately the straight line horizontal length of the conventional window sill garnish mold with its bottom longitudinal edge and adjacent portions extending to a greater length than the upper outer portion of the cover.

3. For use with an automobile window frame having a glass vent pivoted therein with a weatherstrip below the vent and a conventional garnish mold extending along the lower edge of the window frame and beneath the weatherstrip, a cover for the garnish mold comprising a resilient strip transversely bowed and having a flange along its upper longitudinal edge only at its intermediate portion leaving flangeless upper edge portions which are flattened and adapted to be interchangeably inserted beneath the weatherstrip, said strip also having a lower edge flange, said flanges being separated in the unsprung condition of the strip a lesser distance apart than the dis-

tance between opposite longitudinal edges of the garnish mold whereby the strip may be snapped in place over the garnish mold, and said lower flange being trough-shaped and made up of substantially parallel walls with a curved bottom wall joining the same.

4. For use with an automobile window frame having a glass vent pivoted therein with a weatherstrip below the vent and a conventional garnish mold extending along the lower edge of the window frame and beneath the weatherstrip, a cover for the garnish mold comprising a resilient strip transversely bowed and having a flange along its upper longitudinal edge only at its intermediate portion leaving flangeless upper edge portions which are flattened and adapted to be interchangeably inserted beneath the weatherstrip, said strip also having a lower edge flange, said flanges being separated in the unsprung condition of the strip a lesser distance apart than the opposite longitudinal edges of the garnish mold whereby the strip may be snapped in place over the garnish mold, and said lower flange being trough-shaped and made up of substantially parallel walls with a curved bottom wall joining the same, the ends of said cover strip being curved and the upper flange extending substantially vertically and the lower flange wall extending at approximately 45° to the part from which it is bent.
